BOMB SHELTER

Jacob Feld, Mount Vernon, N. Y., assignor to
Bomb Shelter, Inc., Bayside, N. Y., a corpora-
tion of New York

Application February 20, 1951, Serial No. 14,281

Term of patent 3½ years

(Cl. D13—1)

To all whom it may concern:

Be it known that I, Jacob Feld, a citizen of the United States, residing at 16 Mersereau Avenue, in the city of Mount Vernon, county of Westchester, and State of New York, have invented a new, original, and ornamental Design for a Bomb Shelter, of which the following is a specification, reference being had to the accompanying drawing, forming a part thereof.

Fig. 1 is a top plan view of a bomb shelter showing my new design; and

Fig. 2 is an end view of the bomb shelter.

I claim:

The ornamental design for a bomb shelter, as shown.

JACOB FELD.
